United States Patent Office.

JAMES T. CARSON, OF GREENSBORO, NORTH CAROLINA.

Letters Patent No. 74,197, dated February 11, 1868; antedated January 6, 1868.

IMPROVED BELT-PUNCH.

The Schedule referred to in these Letters Patent and making part of the same.

TO ALL WHOM IT MAY CONCERN:

Be it known that I, JAMES T. CARSON, of Greensboro, in the county of Guilford, and State of North Carolina, have invented a new and improved Combination Belt-Punch; and I do hereby declare that the following is a full, clear, and exact description thereof, which will enable others skilled in the art to make and use the same, reference being had to the accompanying drawings, forming part of this specification.

This invention relates to a combination of tools, which are especially adapted to use in making and mending belts, in factories and other places where belts are used, and the invention consists in combining the common belt-punch with a knife, an awl, and a punch-head, as will be hereinafter described.

Figure 1 represents the instrument complete, with the knife-blade ready for use, and the punch thrown back.

Figure 2 shows the knife-blade closed, and the punch ready for use, both figures being side views.

Figure 3 is an edge view, showing the back of the knife-blade.

Similar letters of reference indicate like parts.

A represents the awl, which is oval in shape, and tapering to a point, as seen in the figures. The handle of the awl, which is marked B, is the part to which the other portions are attached. It is split or parted, something like a pocket-knife handle, as seen in fig. 3. C is the punch. D is the head of the punch, the end of which forms a hammer-head. E is the knife-blade. The punch is screwed into the head, D, and different-sized punches may be fitted and screwed into the same socket. The head is drilled through to the offset a, for the discharge of the chips, the hole being seen in dotted lines in fig. 1. The head, D, has two ears, b b, by which it is attached to the handle B of the awl, by a pin, c. This pin is the pivot upon which the head turns, and also the one upon which the knife-blade turns. f is a spring, attached to the handle B, at d. It is double, as seen in fig. 1. One portion is the spring for the knife-blade, and the other portion acts upon the head, D, bearing against it, and holding it in place at all times. This spring is plainly shown in figs. 1 and 2. The different parts and their combination are so plainly shown in the drawing, that further description is deemed unnecessary.

Having thus described my invention, I claim as new, and desire to secure by Letters Patent—

The combination belt-punch, constructed as described, consisting of the awl A; having the handle B split to receive the knife-blade E, the adjustable hammer D, carrying the punch C, with its ears, b; fitting over said handle, and pivoted thereto, the spring f, secured, at d, in the handle B, and operating the knife-blade and punch, substantially as herein set forth, for the purpose specified.

JAMES T. CARSON.
